UNITED STATES PATENT OFFICE.

JESSE A. LOCKE, OF MILFORD, MASSACHUSETTS, ASSIGNOR OF TWO-THIRDS
TO THOMAS P. WILKINSON, OF SAME PLACE, AND FREDERICK S. SHEPHERD,
OF NEW YORK, N. Y.

PRESSER-FOOT-LIFTING DEVICE FOR SEWING-MACHINES.

SPECIFICATION forming part of Letters Patent No. 424,010, dated March 25, 1890.

Application filed November 12, 1889. Serial No. 330,049. (No model.)

To all whom it may concern:

Be it known that I, JESSE A. LOCKE, of Milford, county of Worcester, State of Massachusetts, have invented an Improvement in 5 Presser-Foot-Lifting Devices for Sewing-Machines, of which the following description, in connection with the accompanying drawing, is a specification, like letters on the drawing representing like parts.

- 10 In the manufacture of head-covering from braid upon a sewing-machine it is customary to lift the presser-foot automatically when the feed is to take place, especially when the circular part of the covering, called the "tip," is 15 being started; but in practice I find that better results may be attained by lifting the presser-foot to a point at which it will produce but little, if any, friction on the braid and keep it elevated while the tip is being 20 made, and so, also, by lifting the presser-foot two braids can be connected end to end, which cannot be well done on straw-braid machines as now made, unless the operator reaches over the machine and lifts the presser-foot by the 25 usual presser-foot-elevating lever.

- I do not herein claim, broadly, a presser-foot lifter; but prior to my invention I am not aware that a presser-foot lifter made as a wedge and arranged at the back of the machine has ever been connected with a vertical lever having a handle located near the bed-plate and readily accessible to the hand of the operator while guiding and manipulating the work.

- 35 The drawing in elevation represents a sufficient portion of the rear side of a straw-braid-sewing machine of usual construction to enable my invention to be understood.

- The drawing represents my improvement 40 applied to a straw-braid-sewing machine, substantially such as represented in United States Patent No. 218,413.

- In the drawing, A represents the constructional frame-work of the machine. A² is supposed to represent the cloth-plate, upon which the braid to be sewed rests; A³, the usual hook-shaft; A⁴, the usual cam for operating the feed; A⁵, a link; A⁶, the needle-bar-actuating arm; A⁷, the needle-bar; A⁸, the presser- 50 foot bar, and A⁹ the usual presser-foot com-

monly employed for sewing straw braid, it having at its front end nearest the operator any usual separator (not shown) for the braid, the edge of the overlapping braid resting against the guide a, carried by the presser- 55 foot, all as in the said patent.

The presser-foot bar near its upper end has a stud or projection b, between which and the bearing b', in which the presser-foot bar rises and falls, I have interposed a lifting wedge-bar b², having a lip or shoulder 20 to prevent it from being drawn out from under the projection b, the said wedge being jointed at b³ to a vertical lever b⁴, pivoted at b⁵ on the overhanging arm of the frame-work, the lower end 60 of the said lever having a suitable hand-piece b⁶ bent toward the operator and lying near the level of the cloth-plate A², so that the operator with but a slight movement of the hand may engage the said handle and turn the 65 lower end of the said lever toward the rear end of the machine, as represented by dotted lines, whenever it is desired to lift the presser-foot and relieve its pressure from the braid lying upon the cloth-plate A², which it is nec- 70 essary to do when the top or center of the crown of a hat or bonnet is being stitched, or when the two ends of a piece of straw or other braid are abutted together to be stitched. The upper inclined side of the wedge when 75 moved from the full-line into its dotted-line position acts to lift the presser-bar and presser-foot, the distance to which the presser-foot is lifted depending upon the extent of movement of the said wedge, the presser-foot being lifted more or less, according to the thickness of the braid being stitched.

In practice the presser-foot will be lifted and retained lifted at a distance above the cloth-plate just sufficient to receive the braid 80 to be stitched, it being kept in such position until after the tip has been formed, when the presser-foot will be allowed to descend upon the material, it being kept down thereon by the action of the usual spring c.

Prior to my invention, as in said patent, a straw-braid-sewing machine has been provided with a vibrator to automatically lift the presser-foot a definite distance while the tip is being made; but in practice I have found 85 90 95 100

that the tip can be better and more readily made by lifting the presser-foot just high enough to touch the top of the uppermost braid, whatever may be the thickness of the two layers of the braid and keeping it in such position while the tip is being made and while any piecing is being done, during which times the braid is not subjected to any friction to stretch it out of shape or tend to retard the movement of braid when it is being shaped.

I am aware that the presser-bar of a sewing-machine has been surrounded by a cam-shaped collar, rotation of which lifts the presser-foot; but the handle of the cam has always been located at the rear side of the machine, where it can be reached only by considerable effort on the part of the operator, and the cam is not so shaped as to leave the presser-foot in any desired location. The friction of the lever b^4 on the stud b^5 is sufficient to aid in keeping it in adjusted position.

I do not desire to limit my invention to the exact shape of the lip or shoulder to prevent the wedge from being wholly withdrawn from under the projection b of the presser-bar.

I claim—

1. The combination, with the presser-foot, the presser-bar having a stud or projection b ,

a lifting-wedge b^2 , and a lip or shoulder to prevent the wedge from being withdrawn from under said projection b , of a pivoted lever, to which the said lifting-wedge is jointed, the said lever terminating at one side of but near the cloth-plate in position to be readily engaged by the operator when it is desired to place the presser-foot at any determined level and retain it there for a number of stitches, for the purposes set forth.

2. The combination, with the presser-foot, the presser-bar having a stud or projection, and the presser-bar-lifting wedge b^2 , of a pivoted lever, to which the said lifting-wedge is jointed, said lever terminating at one side of but near the cloth-plate in position to be readily engaged by the operator when it is desired to place the presser-foot at any determined level and retain it there for a desired length of time, as and for the purposes set forth.

In testimony whereof I have signed my name to this specification in the presence of two subscribing witnesses.

JESSE A. LOCKE.
